Application June 28, 1950, Serial No. 170,761

25 Claims. (Cl. 216—57)

1

This invention relates to labeling machines, and more especially to article-registering mechanism for accurately locating an article to receive a label.

In applying labels to certain types of article it is required to deposit the label accurately with relation to some feature of the peripheral surface of the article. For instance, some bottles have raised characters or words with reference to which the label must be accurately located. For further example, cans may have a longitudinal seam and the label must be placed so that its dominating word or picture is diametrically opposite to the seam.

Mechanism commonly known as a spotting device has heretofore been devised for orienting the article as the latter approaches the label-affixing device, with the object of presenting the desired area of the article for the reception of the label. Devices of this general type are disclosed, for example, in the patents to Essen, No. 2,222,503, November 19, 1940, and Carter, No. 2,426,433, August 26, 1947; and such mechanisms are wholly acceptable for the intended purpose except under certain special conditions.

Some bottles, for example, in addition to the main label, are provided with relatively small medallion-like labels, sometimes bearing merely a monogram or trade mark, and sometimes of a diameter of the order of $\frac{3}{4}$ ", and it is quite customary, when such small labels are employed, to provide the bottle with a depression in its outer surface or a raised ridge defining a space just large enough to receive this small label. In order to insure the deposit of this small label within such a restricted area, it is requisite that this small area of the bottle be registered with extreme accuracy as respects the label-affixing means, since otherwise the label will not be centered and will overlap the edge of the area to which it should be affixed, thus producing an unsightly appearance.

Orienting or spotting mechanism of the customary prior types occupy substantial space and cannot be located within the confines of the label-affixing mechanism. Thus such orienting or spotting mechanism is usually located just ahead of the affixing mechanism and operates to orient the article as it approaches the affixing mechanism. However, after the article has been properly oriented, the article must move along an appreciable distance before it reaches the label-affixing point. During this further travel it may

turn a few degrees in one direction or another by reason of unbalanced frictional contact with the guide rails of the conveyor or because of vibration or the like. In applying the ordinary label, such slight turning of the article is usually of no particular importance but when, as above suggested, a very small label must be placed within a defined correspondingly small area of the peripheral surface of the article, an error in registry resultant from rotation of the article of so little as 5°, for example, may result in improper placing of the label.

One object of the present invention is to provide an article registering mechanism operative accurately to position an article and to hold it firmly in place until the label has been applied. A further object is to provide article-registering means, adjunctive to usual spotting mechanism, operative to restore an article, previously oriented but which has turned slightly, to its proper position of orientation and to hold it so positioned while the label is being affixed. A further object is to provide article-registering mechanism, in cooperation with a conveyor of the intermittent feed type, which is actuated by the conveyor mechanism and in time with the latter. A further object is to provide an article registering mechanism comprising opposed article-engaging parts which move toward each other to place an element of the article interposed between them at a definite centered position. A further object is to provide article registering means so devised that it may be located at the label-affixing point and so that no portion of the mechanism projects above the conveyor path sufficiently to interfere with the label-applying mechanism. Other and further objects and advantages of the invention will be pointed out in the following more detailed description and by reference to the accompanying drawings wherein.

Fig. 1 is a diagrammatic plan view of a conveyor designed to convey articles, for example bottles, to and from label-applying apparatus;

Fig. 2 is a side elevation of a bottle having a relatively small defined area designed for the reception of a label;

Fig. 3 is a rear elevation of the bottle of Fig. 2, showing a spotting projection arranged diametrically to the label-receiving area;

Fig. 4 is a fragmentary side elevation, partly in vertical section, of the conveyor device of Fig. 1, showing the apparatus of the present invention;

Fig. 5 is a fragmentary plan view, to larger scale, of the apparatus of the present invention, the parts being in the position which they occupy as the bottle is delivered into the labeling station;

Fig. 6 is a view similar to Fig. 5, but to still larger scale, showing the apparatus of the present invention with the parts in the position which they occupy at the completion of the bottle-registering operation;

Fig. 7 is a vertical section, partly in elevation, substantially on the plane of the line 7—7 of Fig. 4;

Fig. 8 is a fragmentary side elevation of the apparatus of the present invention, the parts being shown in the position in which they appear in Fig. 6;

Fig. 9 is a plan view of one of the registering jaw levers removed from the machine; and

Figs. 10, 11 and 12 are diagrammatic plan views illustrating the operation of the registering jaws.

The present invention is illustrated by way of example as associated with a conveyor mechanism of the general type of that disclosed in the patent to Holm 2,026,172, December 31, 1935, the conveyor there shown being of the intermittent feed type in which the articles are moved forwardly step by step and dwell between successive steps. Since the specific mechanism for feeding the bottles in this manner is old and well known and illustrated and described by way of example in the patent to Holm, it is unnecessary to describe the feed mechanism in detail. It suffices to point out that the articles are advanced along substantially parallel rails 12 and 12^a (Fig. 1) by a feed bar 13 intermediate the rails 12 and 12^a and which has imparted to it a movement of the so-called "four-motion feed" type in which the bar rises to lift an article from the rails 12 and 12^a then moves along in the direction of article advance, then descends to allow the article to rest on the rails 12 and 12^a, and then, in its lowered position, returns to its starting point, then again rising and repeating the cycle. As illustrated in Fig. 4 the up and down motion of the feed bar 13 is occasioned by a plurality of reciprocating cams 14, 14^a, etc., which are connected by a rod 14^b and which are moved horizontally by motion-transmitting means actuated by a rotary cam on the shaft C which is driven in properly timed relation to the mechanism for applying labels.

Referring to Fig. 1, it is assumed that the articles are delivered so as to rest upon the rails 12 and 12^a at the right-hand side of the view and are advanced in the direction of the arrow W. The articles to be labeled, here shown as bottles B (Figs. 2 and 3) are of a special kind, having a definitely defined area A, for example an area bounded by a projecting annular rib within which is to be placed a label L. Since the area provided to receive the label L may be of small diameter, for example, $\frac{1}{2}$ ", and since the label L is intended to register exactly with this area, it is necessary that the bottle be placed in exact registry with the label-applying element in order that the label L may be centered with respect to the area A. The bottle may have other labels such as the label L¹ (Fig. 2) affixed to it, but the proper application of a label, such as the label L¹, to an extended area of the peripheral surface of the bottle can be assured by the use of usual spotting mechanism, whereas the application of a label such as the label L to such a particular defined area as the area A does require very careful orientation of the bottle.

It is customary to provide the bottles with so-called "spotting" projections or "tear drops" P (Fig. 3) to assist in registering the bottle in preparation of the application of a label and spotting mechanism for so orienting the bottle is well known. Such spotting mechanism is illustrated by way of example in the patent to Carter 2,426,433, August 26, 1947, and such a spotting mechanism is indicated at the station 15 (Fig. 1) 5 where the bottle B^x is shown as being oriented so that its spotting projection P shall be positioned exactly in that vertical radial plane of the bottle which is perpendicular to the conveyor path.

For usual labeling operations this spotting operation may be sufficient and no further registering operation may be required, but when the bottle is of the type shown in Fig. 2 where the label L must be applied very exactly to a small area, it sometimes occurs that the bottle turns 10 slightly after leaving the spotting station 15 before it reaches the label-applying station 16.

At the label-applying station 16, to which the articles are delivered by the conveyor after leaving the station 15, there is provided applying mechanism 21 which may be of conventional type and which includes a label-applying element 22. This label applying element may be a picker, transfer pad or any other usual device common in the labeling art for placing the label in contact with the article designed to receive it. Ordinarily this label-applying part 22 rocks about a horizontal axis and the center of symmetry of that face of the applying device to which the label adheres moves in a vertical plane accurately radial to the bottle and perpendicular to the conveyor path, the plane being herein designated as the plane G, and it is requisite in dealing with a bottle such as shown in Fig. 2 that the center of the area A to be accurately located 25 in this radial plane. It will be understood that the label carried by the applying element (picker or transfer pad) should be so placed thereon as to be accurately centered with reference to the plane G, and for convenience in description and in the claims it is assumed that the center of the label actually coincides with the center of symmetry of the applying element.

The spotting projection P of the bottle is disposed diametrically opposite to the label-receiving area A, and in the radial plane of the center of said area, and, as here illustrated, this spotting projection is at the opposite side of the bottle from the label-applying device 22 at the station 16.

55 As shown in Fig. 1, the label is first applied to the bottle at the station 16 and then the bottle is transferred by the conveyor to the next station 17 where another operation may be performed, for example, a label-applying mechanism 23 having a picker or transfer pad 24 may apply another label or may merely apply pressure to the label applied. From the station 17 the bottle B^x is advanced to the station 18, as shown at position B^y, and where it is pushed transversely 60 off of the conveyor by a pusher 19 and onto a delivery conveyor 20.

At the station 16, in accordance with the present invention, a bracket 25 (Fig. 8) is bolted to the upper surface of the table T upon which the conveyor mechanism is mounted, this bracket 25 having bearings for two horizontal parallel shafts 26 and 27 (Fig. 7) disposed at the front and rear, respectively, of the conveyor (the rear being here referred to as that side at which the label-applying mechanism 21 is located). These shafts 26 70

75

and 21 form pivotal supports for two carriers 28 and 29, respectively. These carriers are provided with upwardly projecting pins 30 and 31 (Figs. 5, 6 and 8) upon which are mounted cam follower rolls 32 and 33, respectively. These cam follower rolls are designed to be engaged by cam edges 34 and 35 of a cam plate 36 which is mounted on a bar 37 which is fixed to the reciprocating cam members 14 and 14^a (Fig. 4) so as to partake of the longitudinal motion of said cam members. A coiled tension spring 38 (Figs. 5 and 6) connects the pins 30 and 31 and thus tends to swing the upper edges of the carriers 28 and 29 toward each other; that is to say, toward the conveyor path. It may be noted, by reference to Fig. 7, that the cam follower rolls 32 and 33 and the cam plate 36 are located well below the rails 12 and 12^a so that they do not contact an article traveling along the conveyor path.

The carrier 29 (Figs. 5, 6 and 7) supports a carriage 29^a which is adjustable in a path parallel with the conveyor path and which may be fixed in adjusted position by a set screw 42^a. The carriage has spaced, upstanding, vertical pins 39 and 40 carrying freely rotatable abutment rolls 41 and 42. These rolls are spaced apart and the carriage is so adjusted that the axes of the rolls are at accurately equal distances from the plane G (Figs. 5, 10, 11 and 12) of movement of the label-applying element 22, these rolls 41 and 42 being designed to engage the peripheral surface of the bottle B at the labeling station and to center it relative to the head grips and supports it against the rearwardly exerted pressure of the registering jaws.

The forward carrier 28 is provided with an upward extension 43 (Figs. 7 and 8) having a horizontal guide slot which receives a rib projecting downwardly from a carriage 44 which is designed for adjustment longitudinally of the conveyor, with reference to the part 43, by means of a set screw 45. When once adjusted the part 44 is rigidly secured to the part 43 by a set screw 45^a.

The part 44 is provided with two upwardly directed arms 46 and 47 (Fig. 8) which carry parallel, upwardly directed pins 48 and 49 on which are mounted jaw levers 50 and 51 (Figs. 5, 6 and 9). These levers 50 and 51 are alike except that one is reversed relatively to the other. Each of these jaw levers (Fig. 9) is provided with a bore R for the reception of the corresponding pin 48 or 49 and is provided with a screw-threaded bore for the reception of the end of the screw-threaded stem 52 of the corresponding jaw 53, the latter having a flat end face 54 and a tapering peripheral face 55. Each lever is also provided with an arm 56 having a hole 57 near its end, and with a stop arm 58. A coiled tension spring 59 (Figs. 5 and 6) has its opposite ends hooked into the holes 57 in the respective levers 50 and tends to draw the arms 56 toward each other. Such motion of the levers is limited by engagement of the arms 58 with stop pins 60 (Figs. 5 and 6) projecting from the parts 46 and 47. When the parts 58 engage the stop pin 60 the axes of the stems 52 of the jaws 53 are inclined to each other at an angle of the order of 120° (Figs. 5 and 10), the apex of this angle lying in the plane G (Fig. 10) of movement of the label-applying element 22.

In the operation of the apparatus, and assuming that a bottle B^x will be oriented by the spotting mechanism at the station 15 so that its spotting projection P will be placed in a plane perpendicular to the conveyor path, and that this bottle will then be advanced toward the station 16, the

advancing movement of the rail 13 which is to deliver the bottle into the station 16 is accompanied by such a movement of the bar 37 that the cam plate 36 will have been entered between the rolls 32 and 33 (Fig. 5) so as to separate the upper portions of the carriers 28 and 29 just before the bottle enters the labeling station 16. The bottle is thus free to enter the labeling station without contacting the rolls 41 or 42 or the jaws 53. The bottle now comes to rest in the labeling station 16 and it is assumed that the projection P will not have been displaced from the position in which it was placed by the spotting mechanism more than the distance between one or the other of the jaws 53 and the plane G of operation of the label-applying element 22. As shown in Fig. 10 the projection P is to the left of the plane G and located close to the left-hand jaw 53.

Once the bottle has been deposited within the label-applying station, the feed bar 13 descends and moves back toward its starting point and during such movement the cam plate 36 moves back to the position shown in Fig. 6 thereby permitting the spring 38 to move the upper portions of the carriers 28 and 29 toward each other. The cam edge 35 is so shaped that the rolls 41 and 42, supported by the rear carrier 29, first move in and contact the peripheral surface of the bottle B, thereby centering the bottle with respect to the head grip H (Fig. 4) and so that the axis of the bottle is in the plane G. The cam surface 34 then permits the forward carrier 28 to move inwardly. As it moves inwardly, the jaws 53 first contact the periphery of the bottle B to their inner corners 53^a (Fig. 10). It being assumed that the spotting projection P is to one side of the plane G but within reach of the jaws 53, the continued inward movement of the front carrier 28 will cause the tapered edges of the jaws 53 to press upon the peripheral surface of the bottle, and, due to the angle of inclination of the stems 52, the levers 50 and 51 begin to swing and the jaws slide along the peripheral surface of the bottle toward each other, the beginning of this motion being indicated in Fig. 11. This sliding motion of the jaws, in contact with the peripheral surface of the bottle, which acts as a cam during this motion, causes the jaws to approach each other and that jaw which is nearest to the projection P engages the projection and turns the bottle about its axis until, when the carriage has reached its innermost position and the stems 52 of the jaws are substantially aligned with each other (Fig. 6), the projection P has been brought to lie accurately in the plane G of movement of the label-applying element 22 (Fig. 12). While the parts dwell in this position, the element 22 applies the label to the area A of the bottle and then retracts and immediately thereafter the feed rail 13 rises to advance the bottle from the station 16 to the station 17. During such motion the cam plate 36 is again advanced to separate the carriers 28 and 29, thus permitting the bottle to pass freely from the station 16. During the retreat of the carriers 28 and 29 from the conveyor path, the spring 59 restores the levers 56 to the normal position shown in Fig. 5.

The above operation is repeated, cycle after cycle, each bottle as it dwells at the labeling station 16 being accurately registered and held firmly in place by the jaws while the label is being applied. In that type of labeling machine where in the label is adhered to the article at one station and then wiped down at a succeeding station, such a registering apparatus as that of the

present invention may be associated with each of said stations, if desired.

As previously noted, the present invention concerns a device, adjunctive to a spotting mechanism (which may be of conventional type), and is designed to correct slight changes in orientation of the bottle while the latter is on its way from the spotting mechanism to a successive working station. Since the device of the present invention is designed to correct small errors, only, it is important that the spotting mechanism be located as closely as possible to said successive working station so that the amount of accidental orientation of the bottle, after leaving the spotter, may not exceed the angle included between the faces 54 of the jaws 53 when the latter are in the inoperative position shown in Fig. 5.

While one desirable arrangement of parts has herein been illustrated and described, it is to be understood that the invention is broadly inclusive of any and all modifications which fall within the scope of the appended claims.

I claim:

1. A labeling machine of the kind which includes a movable label-applying device, means for moving the applying device thereby to apply a label to an article, and, in combination therewith, means comprising spaced, relatively movable article-engaging parts operative to orient an article while the article is within the field of action of the applying device, and means for actuating said parts.

2. A labeling machine of the kind which includes a movable label-applying device, means for moving the applying device to apply a label to an article, and, in combination therewith, means, comprising spaced article-engaging jaws and means for moving them toward each other, operative to orient an article while the article is within the field of action of the applying device and to hold the article locked against rotation while the label is being applied.

3. A labeling machine of the kind which includes a label-applying device which moves in a predetermined plane, means operative to deliver an article having a peripheral projection into the field of action of the label-applying device, and, in combination therewith, means, comprising a support movable toward the article and relatively movable jaws carried by the support, operative to turn the article while the latter is in the field of action of the label-applying device until its projection is accurately located in the plane of movement of said applying device.

4. A labeling machine designed to apply a label to a particular area of a bottle which has a peripheral projection diametrically opposite to said area, the machine being of the kind which includes a label-applying element movable in a radial plane of the bottle, and, in combination therewith, means, comprising a support movable toward and from one side of the bottle, an abutment engageable with the opposite side of the bottle and projection-engaging jaws carried by the support operative, while the bottle is within the field of action of the label-applying element, to turn the bottle until said projection is accurately located in said radial plane.

5. A labeling machine of the kind which includes means operative to deliver to a label-applying station an article which has already been approximately oriented for the reception of a label, and, in combination therewith, means, comprising a carrier and an abutment, means for moving the carrier and abutment toward the

article from opposite sides of the latter, while the article dwells at said station, and article-engaging jaws mounted on the carrier, operative, while the article dwells at said station to impart a final and accurate orientation to the article thereby to insure application of the label to that particular area of the article which is designed to receive it.

6. A labeling machine of the kind which includes means operative to deliver to a label-applying station, an article which has already been approximately oriented for the reception of a label, and, in combination therewith, means, comprising relatively movable article-engaging jaws and means for moving the jaws toward each other, while in contact with the article dwelling at said station, and which is operative, while the article continues to dwell at said station to impart a final and accurate orientation to the article and to prevent any further rotation of the article while it dwells at said station.

7. In a labeling machine of the kind having a label-applying element which moves in a predetermined path toward and from the article to be labeled while the latter dwells at a label-applying station, means for correcting the orientation of an article having a peripheral spotting element after said article has been delivered in approximately oriented position into the field of action of the label-applying element, said correcting means comprising jaws engageable at opposite sides of the projection, and means for moving the jaws in opposite directions toward the path of movement of the label-applying element.

8. In a labeling machine of the kind having a label-applying element which moves in a predetermined path toward and from an article to be labeled while the latter dwells at a label-applying station, means for correcting the orientation of a bottle having a particular area for the reception of a label and having a peripheral projection diametrically opposite to said area, after said bottle has been delivered in approximately oriented position to the label-receiving station at which the label-applying element moves in a radial plane of the bottle, said correcting mechanism being operative, while the bottle is at said label-receiving point, to turn the bottle until its projection is accurately located in said radial plane, said correcting means comprising opposed jaws arranged to receive the projection between them, and means for moving said jaws toward said radial plane.

9. Mechanism for correcting the orientation of articles each having a spotting projection and which are delivered, one by one, into a station, where it dwells temporarily, after having been spotted so that the projection occupies a definite position of orientation, said correcting mechanism being associated with said station and being operative to restore the article to said definite position of orientation if the article has turned, after being spotted and before it reaches said station, said correcting mechanism comprising a pair of spaced projection-engaging parts, means to contact said parts with the article at opposite sides, respectively, of the projection, and means for moving said parts toward each other.

10. Mechanism for correcting the orientation of an article which, after having been spotted to turn it until it occupies a definite position of orientation, is moved to a station where it dwells temporarily, said correcting means being located at said station and being operative to restore the article to said definite position of orientation if

the article has turned after being spotted and before it reaches said station and to hold it in said position while it dwells at said station, said correcting mechanism comprising relatively movable parts, means for moving them into contact with the article at spaced points respectively, and means for causing said parts to approach while in contact with the article.

11. Mechanism for correcting the orientation of articles each having a peripheral projection as they move along a path from one station to another, each article stopping temporarily at each station and being spotted at one station so that its projection occupies a certain position of orientation, said correcting mechanism being located at a succeeding station and being operative, while the article remains at said latter station, to restore the projection to said position of orientation if the article has turned in moving from the spotting station to the last-named station and to hold it in said position while the article continues to dwell at said station, said correcting mechanism comprising a carrier movable toward and from the article, a pair of spaced projection engaging elements mounted on the carrier, and means for moving said elements toward each other with the projection interposed between them.

12. Mechanism for correcting the orientation of articles each having a peripheral projection as they advance along a path from one station to another, each article stopping temporarily at each station and being spotted at one station so that its projection occupies a definite position of orientation, said correcting means being operative to reestablish the position of orientation after the article enters a succeeding station, and comprising a pair of oppositely movable elements engageable with the article at opposite sides respectively of the projection, and means for moving said elements bodily toward and from the article, and means for moving them toward and from each other.

13. In a labeling machine of the kind having a label-applying element which moves in a predetermined path toward and from an article to be labeled while the latter dwells at a label-applying station, mechanism for correcting the orientation of a bottle, having a distinctive area for receiving a label and having a spotting projection, while the bottle dwells at a label-applying station where the label-applying element moves in a radial plane of the bottle, said correcting mechanism comprising a pair of jaws operative to engage a part of the bottle and to turn the bottle until said distinctive area is centered on the radial plane of movement of the label-applying element, and means for actuating said jaws.

14. In a labeling machine of the kind having a label-applying element which moves in a predetermined path toward and from an article to be labeled while the article dwells at a label-applying station, mechanism for correcting the orientation of an article having a peripheral projection while the article dwells at a label-applying station where the label-applying element moves in a predetermined plane, said correcting means comprising two jaws located respectively at opposite sides of and at equal distances from the plane of movement of said label-applying element, and means to move said jaws in opposite directions toward the projection on the article thereby to turn the article sufficiently to 10-

cate said projection accurately in the plane of movement of the applying element.

15. In a labeling machine of the kind having a label-applying element which moves in a predetermined path toward and from an article to be labeled while the latter dwells at a label-applying station, mechanism for correcting the orientation of articles, each having a spotting projection and a label-receiving area, while the article dwells at the label-receiving station after having been approximately oriented in preparation for the application of a label to said area, said correcting mechanism comprising a pair of jaws operative to engage a portion of the bottle while the latter is at the label-receiving station and to turn the bottle until said label-receiving area is accurately located for the reception of a label, and means for actuating the jaws.

16. Mechanism for orienting articles, each having a peripheral spotting projection, said mechanism comprising two jaws, means for moving the jaws into contact with an article to be oriented, and means to move the jaws toward each other with the projection on the article between them thereby to turn the article so as accurately to orient said projection.

17. Mechanism for correcting the orientation of articles, each having a peripheral projection, as they advance along a path from one station to another, stopping temporarily at each station and being spotted at one station so that the peripheral projection occupies a certain position of orientation, said correcting mechanism being located at a succeeding station and comprising a pair of opposed projection-positioning jaws and means for actuating the jaws, said jaws being operative by engagement at opposite sides respectively of the projection to correct the position of orientation of the article and to hold it in the corrected position while it dwells at the last-named station.

18. Mechanism for correcting the orientation of articles, each having a spotting projection, as they move along a path from one station to another, stopping temporarily at each station and being spotted at one station so that the projection on the article occupies a predetermined position of orientation, said correcting means being located at a succeeding station and being operative to reestablish said predetermined position of orientation and comprising in combination a pair of normally spaced relatively movable jaws designed to engage the peripheral surface of an article while the latter dwells at the last-named station and at opposite sides respectively of its spotting projection, and means operative to cause the jaws to approach and to grip the projection between them, the jaws being so located that when the projection is firmly gripped between them the article will be so placed that the spotting projection will lie in a plane perpendicular to said path.

19. Article orienting means for use in a machine for applying a label to an article having a peripheral spotting projection, said orienting means comprising two jaws pivotally connected to turn about parallel axes, the jaws being of equal length and normally converging toward each other, a carrier on which the jaws are mounted and which is operative to move them bodily toward an article to be oriented, means for moving the carrier so as to press the free ends of the jaws against the peripheral surface of the article at opposite sides respectively of its

spotting projection thereby to cause the jaws to slide along the surface of the article as they approach, and abutment means engageable with the peripheral surface of the article at the opposite side of the latter from that with which the jaws contact thereby to prevent bodily movement of the article by the pressure of the jaws.

20. Article orienting means for use with a conveyor arranged to advance articles, each having a peripheral spotting projection, along a path and for stopping each article temporarily at a station, said orienting means comprising a carrier arranged at each side respectively of the conveyor at said station, each carrier being arranged to swing about an axis parallel to the conveyor path, a cam moving in time with the conveyor as the latter delivers an article to said station, and which is operative to separate the carriers to allow an article to enter between them, spring means urging the carriers inwardly toward each other while the article dwells at said station, a pair of spaced abutment rolls mounted on one carrier and engageable with the periphery of the article as said latter carrier moves inwardly, a pair of jaws mounted on the other carrier, said jaws being pivoted to swing about parallel axes, a spring tending to hold the free ends of the jaws separated, and stop means limiting such separation of the jaws, the jaws being so arranged that, as the carrier approaches the article, the free ends of the jaws first engage the periphery of the article at opposite sides, respectively, of the projection and then slip along the peripheral surface of the article until they grip the projection between them.

21. Article orienting means for use with a conveyor designed to advance articles, each having a peripheral projection, along a path from a spotting station to another station and for stopping each article temporarily at each station, said orienting means including a pair of normally spaced but pivoted jaws located at the label-applying station, a spring tending to move said jaws apart, a carrier upon which the jaws are mounted, means for moving the carrier thereby to press the ends of the jaws against the peripheral surface of an article at the last-named station with the ends of the jaws located, respectively, at opposite sides of the projection, the jaws normally converging toward each other whereby, as the carrier approaches the article, the ends of the jaws slip along the periphery of the article and approach until they grip the projection between them, and abutment means operative to support the article in opposition to the pressure exerted by the jaws.

22. Mechanism for correcting the orientation of articles, each having a peripheral projection, as they are moving along a path from one station to another, stopping temporarily at each station and being spotted at one station so that the projection on the article occupies a definite position of orientation, said correcting mechanism being located at a succeeding station and being operative, if an article on its way from the spotting station to the last-named station has accidentally turned, to correct the orientation of the article, said correcting mechanism comprising, in combination, a carrier arranged at each side respectively of the conveyor at the label-applying station, said carriers being movable toward and from the conveyor, means operative to move the carriers outwardly as an article enters the station, and means operative to cause the

carriers to approach the conveyor while the article dwells in the label-applying station, abutment means mounted on one carrier and which engages the article as said carrier moves inwardly toward the conveyor, a pair of relatively movable pivoted jaws mounted on the other carrier, spring means tending to separate the free ends of the jaws, said free ends of the jaws being arranged to engage the peripheral surface of the article as the jaw-supporting carrier moves inwardly, the engagement of the ends of the jaws with the peripheral surface of the article causing the jaws to close and grip the projection between them as the carrier completes its movement.

23. Mechanism for correcting the orientation of articles, each provided with a peripheral projection, as they are moved step by step along a predetermined path from one station to another, dwelling temporarily at each station and being spotted at one station so that the projection occupies a predetermined position of orientation, said correcting mechanism comprising a carrier located at a succeeding station and which is movable toward and from the conveyor path, a pair of jaws pivotally mounted on the carrier to swing about substantially vertical axes, a spring tending to separate the jaws, the ends of the jaws being normally spaced apart and directed toward the carrier path and being engageable with the peripheral surface of an article, dwelling at the last-named station, at opposite sides, respectively of the projection, and abutment means at the opposite side of the carrier path from the jaws, the abutment means being operative to support the article in opposition to the pressure exerted on the article by the jaws, the jaws engaging said peripheral surface at such an angle, as the jaw-supporting carrier moves toward the conveyor, that said ends slip along the surface of the article and grip the projection between them.

24. Mechanism for correcting the orientation of articles, each having a peripheral projection, as they move step by step along a predetermined path from one station to another, dwelling temporarily at each station and being spotted at one station so that the projection on the article occupies a predetermined position of orientation, said correcting mechanism comprising a carrier located at a succeeding station and which is movable toward and from said path, a cam for moving the carrier away from said path to allow an article to enter the last-named station, a spring operative to move the carrier toward said path while an article dwells at the last-named station, spaced abutment rolls at one side of said path, said rolls being engageable with the article to prevent it from moving away from the carrier, and means mounted on the carrier and operative as the carrier moves toward said path to turn the article so as to dispose its projection in a vertical plane perpendicular to said path.

25. Mechanism for correcting the orientation of articles, each having a peripheral projection, as the articles advance step by step along a predetermined path from one station to another, dwelling temporarily at each station and being spotted at one station so that the projection on the article occupies a predetermined position of orientation, said correcting mechanism comprising carriers arranged at opposite sides, respectively, of the path at a succeeding station, said carriers being movable toward and from said path, cam means operative to move the carriers away from said path to allow an article to enter the last-named station, spring means operative

to move the carriers toward said path while an article dwells at the last-named station, article-turning elements mounted on one carrier and engageable with the peripheral surface of the article at opposite sides respectively of its projection as said carrier moves inwardly, said elements being constructed and arranged to approach the projection from opposite sides respectively and thereby to move the projection into a plane perpendicular to said path, spaced abutment rolls 10 mounted on the other carrier, and means for adjusting said rolls relatively to their carrier so that

their axes will be spaced at equal distances from said plane.
